DISPLAY CABINET

Stephen V. Bacco, Brooklyn, N. Y., and Malcolm McVickar, Fitchburg, Mass., assignors to The Spool Cotton Company, New York, N. Y., a corporation of New Jersey

Application July 2, 1948, Serial No. 147,344

Term of patent 14 years

(Cl. D80—11)

To all whom it may concern:

Be it known that we, Stephen V. Bacco and Malcolm McVickar, citizens of the United States, residing at Brooklyn, in the County of Kings and State of New York, and Fitchburg, in the county of Worcester and State of Massachusetts, respectively, have invented a new, original, and ornamental Design for Display Cabinet, of which the following is a specification, reference being had to the accompanying drawing, forming a part thereof.

Fig. 1 is a perspective view of the display cabinet showing our new design; Fig. 2 is a side elevational view thereof; and Fig. 3 is a sectional view along the line III—III of Fig. 2.

We claim:

The ornamental design for a display cabinet, as shown.

STEPHEN V. BACCO,
MALCOLM McVICKAR.
